UNITED STATES PATENT OFFICE.

ALBERT L. PITTELKOW, OF ST. PAUL, MINNESOTA.

ATTACHMENT FOR SEWING-MACHINE TABLES.

Application filed March 26, 1920. Serial No. 363,919.

To all whom it may concern:

Be it known that I, ALBERT L. PITTELKOW, a citizen of the United States, residing at St. Paul, in the county of Ramsey and State of Minnesota, have invented certain new and useful Improvements in Attachments for Sewing-Machine Tables; and I do hereby declare the following to be a full, clear, and exact description of the invention, such as will enable others skilled in the art to which it appertains to make and use the same.

My invention has for its object to provide an attachment for power sewing machine tables, which includes lamp-supporting brackets, a conduit for electric light wires, and spool-holding spindles. The purpose of the attachment is to support these various different elements above the table top, so as to leave the table top clear for the work, and at the same time, eliminate a large amount of noise due to vibration.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:—

Fig. 1 is a perspective view of a sectional double-trough table, having the attachment secured thereto;

Fig. 2 is a fragmentary perspective view of one of the conduit sections, with the cover thereof lifted therefrom;

Fig. 3 is a view principally in transverse section taken on the line 3—3 of Fig. 1, on an enlarged scale;

Fig. 4 is a perspective view, in transverse section, taken through one of the conduit sections; and

Fig. 5 is a view in longitudinal central vertical section taken through the connected ends of two of the conduit sections.

The numeral 6 indicates a sectional double-trough sewing machine table having on each side board, of each section thereof, a power sewing machine 7. Said table and sewing machines are of well known standard construction.

The improved attachment includes a plurality of A-shaped brackets 8, which straddle the trough in the table 6, and the legs thereof rest upon the side boards of the

table at the inner longitudinal edges thereof and are rigidly secured thereto by screws.

The brackets 8 have, in their upper extremities, loops 9, in which is mounted a round rod 10. This rod 10 not only connects the brackets 8 and holds the same against movement toward and from each other, but it affords a support for a multiplicity of thread guides 11, each of which has two eyes through which the thread from spools, hereinafter referred to, is extended. These thread guides 11 may be adjusted longitudinally on the rod 10, but, if desired, they may be securely held to the rod by means of staples or other fastening devices. As shown, there is a bracket 8 at the end of the table and at each joint, between the sections thereof. A sectional conduit 12 extends the full length of the table 6 within the brackets 8, and it will be noted that there is a section of this conduit for each section of the table. The conduit 12 is in the form of a channel provided with a removable sectional cover 13, the longitudinal edges of which extend considerably outward of the sides of the conduit, and on the under side thereof are longitudinally extended grooves 13', in which the upper edge portions of the sides of the conduit extend.

Each section of the conduit 12 and each section of the cover 13, is made from a single sheet of metal bent to form the conduit 12 and the grooves 13', in the cover 13. The conduit 12 is secured to the brackets 8 considerably above the table top, by means of stove bolts 14 inserted through aligned holes in the sides of said conduit and the legs of the brackets. The legs of the brackets 8, just above the conduit 12, are bent laterally outward to afford clearance for the extended edge portions of the cover 13.

The adjacent end of the conduit sections are connected by telescoping the one within the other and inserting stove bolts 15 through coincident longitudinally extended slots 16 in the sides of said sections. The adjacent ends of the cover sections are connected by overlapping the same and inserting a long stove bolt 17 through coincident longitudinally extended slots 18 formed therein and correspondingly formed slots 19 in the bottoms of the conduit sections. The upper and lower edges of the sides of the ends of the conduit sections, which are telescoped into the adjacent conduit sections, are beveled to permit vertical annular

movement of said conduit sections in respect to each other. The purpose of the longitudinal slots 16, 18 and 19 is to compensate for any irregularities in the alignment of 5 the table sections or in the varying lengths thereof.

Secured to each cover section is a plurality of upright longitudinally spaced spool-holding spindles 20. In Fig. 1, a spool 10 21 is shown on one of the spindles 20 and the thread 21', wound thereon, extended through the eyes in one of the thread guides 11, and from thence, it will be extended to one of the sewing machines. The thread 15 guides 11 not only hold the thread above the table top, where it is out of the way, but act as sort of tension devices to prevent the thread from unwinding too fast from the spools.

20 At substantially the longitudinal center of each conduit section, is a double lamp-supporting bracket 22, which is in the form of an inverted yoke of such size as to fit closely against the bottom and sides of the conduit 25 and is secured to the bottom thereof by stove bolts 22'. The ends of the brackets 22 extend horizontally outward at the top of the conduit 12 with the projecting edge portions of the cover 13 resting thereon and are secured thereto by stove bolts 23. In each 30 end of each bracket 22 is a hole 24 to receive the curved inner end of a longitudinally contractable and extensible lamp-supporting arm 25 having on its outer end an electric lamp 26 and shade 27. The lamp-supporting arms 25 are tubular and each 35 comprises telescopically connected members held by a set screw 28 in different longitudinal adjustment.

40 Main electric light wires 29 are laid in the conduit 12 and branch lamp cords 30, for each lamp 26, are secured thereto. These branch lamp cords 30 are arranged in groups for the two lamps on each table section, extend through bushings 31 in the bottom of the conduit 12, and the tubular lamp-supporting arms 25, and are attached to the lamp terminals. There must, of course, be sufficient slack in the lamp cords 45 30, between the bushings 31 and lamp-supporting arms 25, to permit the required longitudinal adjustment of said arms. The curved inner ends of the lamp-supporting arms 25, by their biting interlocking engagement with the brackets 22, hold the lamps 50 26 in various different adjustments in respect to the sewing machines.

From the above description, it is evident 60 that a sewing machine table, equipped with my attachment, which supports the electric light wires, lamp cords, lamps, lamp brackets and spools above the table top, leaves the table free for the work so that the same can be easily handled. It also dispenses 65 with the customary spool stands, which are

very noisy, due to vibration. The attachment can be very easily attached to tables of standard make, and the electric light wires and cords may be placed in the conduit and the necessary connections made before the cover is placed on the conduit. In case it is necessary to make repairs, changes or additions to the electric light wires or cords, the conduit cover may be easily removed to expose the same.

70 75 What I claim is:

1. In combination with a sewing machine table having a trough extending centrally thereof, a bracket having members adapted to be attached to said table straddling said trough, said members converging above said table, and a conduit for electrical conductors disposed between and supported by said members above said trough.

2. In combination with a sewing machine 85 table having a trough extending centrally thereof, a bracket having legs adapted to be attached to said table at each side of said trough, said legs converging above said trough, a conduit supported between said 90 legs above said trough intermediate the height of said bracket, said legs converging and connected together above said conduit and supporting a bar adapted to carry 95 thread guides.

3. A device of the class described having in combination a sewing machine table, a conduit extending longitudinally of the table, brackets on the table for supporting the conduit thereabove, angularly and longitudinally adjustable lamp-supporting brackets on the conduit, a removable cover for the conduit, and spool-supporting spindles on the conduit cover.

4. The combination with a double-sided 105 sewing machine table having a central trough therein, of a conduit extending longitudinally of the table, brackets on the table for supporting the conduit thereabove straddling said trough, double lamp-supporting brackets on the conduit extending at 110 each side thereof, and an outlet in the bottom of the conduit in the vicinity of each double lamp-supporting bracket.

5. The combination with a sectional sewing machine table, of a sectional conduit extending longitudinally of the table, brackets on the table for supporting the sectional conduit thereabove, means for adjustably connecting the sections of the conduit, and 120 a sectional displaceable cover for the conduit.

6. The combination with a sewing machine table, of a conduit extending longitudinally of the table, brackets on the table for supporting the conduit thereabove, spool-supporting spindles on the conduit, a rod connecting the brackets above the conduit, and thread guides on the rod.

7. The combination with a sewing machine 130

table adapted to have a plurality of machines disposed in spaced relation therealong, of a plurality of brackets on said table in spaced relation, each bracket comprising relatively narrow diverging legs secured at their lower ends to said table, and means carried by said brackets adapted to support thread and guiding means therefor.

8. The combination with a sewing machine table adapted to have a plurality of sewing machines spaced therealong, of a conduit for electrical conductors extending longitudinally of the table, brackets on said table for

supporting the conduit thereabove, lamp supporting brackets mounted on the conduit, 15 angularly and longitudinally adjustable lamp carrying members supported by said last mentioned brackets, and an outlet in said conduit in the vicinity of each of said lamp supporting brackets.

9. The structure set forth in claim 1, and spool holding and thread guiding means supported by said conduit and members, respectively.

In testimony whereof I affix my signature.
ALBERT L. PITTELKOW.
